MILL ROLL

Arduo L. Nicolai, North Tarrytown, N. Y., assignor to
United States Rubber Company, New York, N. Y., a
Corporation of New Jersey

Application October 1, 1953, Serial No. 383,621

6 Claims. (Cl. 257—95)

This invention relates to mill rolls of the type used in the rubber industry for milling rubber and other similar materials, and more particularly it relates to such a roll which is provided with means for circulating cooling or heating fluid therein to control the surface temperature of the rolls.

Mill rolls are widely used in the rubber industry to mill rubber and similar materials, and since these materials should be milled at controlled temperatures, the rolls are generally provided with means for circulating water through the roll to control the surface temperature of the roll hence the temperature at which the material is milled. One type of mill roll commonly employed in the rubber industry consists of a cylindrical roll body having a central hole extending therethrough along its axis. Near its peripheral surface, the roll has a plurality of longitudinal bores extending axially therethrough spaced about the periphery of the roll which are adapted for circulation of water therethrough. Each end of each of these bores is connected to the central opening by means of a transverse bore extending through the roll from the individual longitudinal bore to the central opening in the roll. These rolls are cooled by circulating water through the central opening to the transverse bores in one end of the roll, thence through these transverse bores to the longitudinal bores, through which the water is circulated from one end of the roll to the other simultaneously in all of the bores to be then conducted through the transverse bores at that end of the roll to be discharged from the central opening.

The cooling provided in rolls of this type is not as efficient as it might be because the movement of the cooling fluid through the peripheral bores may be sluggish; some of these peripheral bores may pass but little fluid with the result that great quantities of cooling fluid may be used without reducing the effective temperature of the roll in some areas very greatly. Furthermore, the ability of the cooling fluid to cool the rolls is not used to greatest effect in a roll of this sort, so great quantities of cooling fluid are required to provide adequate cooling of the rolls. Although this system is not completely satisfactory, it is generally used because rolls of this type may be constructed with relative ease, and these rolls are sturdy and rugged, which are important factors in mill rolls because of the very great forces exerted on the rolls when they are used to mill rubber.

It is an object of this invention to provide an improved mill roll of this type wherein the fluid is positively circulated through all the longitudinal bores in a manner which provides efficient use of the cooling properties of the fluid. This object is achieved by providing a roll of this type with baffles to be disposed in the central opening of the roll which are adapted to direct the fluid through the peripheral bores sequentially, so the fluid passes through selected ones of the peripheral bores first to one end of the roll, and then back through others of the peripheral bores to the opposite end of the roll. In this manner, the water is passed back and forth along the periphery of the roll through the bores sequentially to insure good flow control

2

of the fluid and good heat transfer to this cooling medium.

A further object of this invention is to provide baffles which may be inserted readily in existing mill rolls of this type to provide this improved cooling system for the roll.

5 This invention contemplates specifically a pair of baffles which are designed to be inserted in the central opening through a mill roll of the type described. A first of these baffles comprises a pair of plates which are disposed on opposite sides of the openings of the transverse bores into 10 the central passage. These plates are adapted to seal off the central passage from communication with the transverse bores excepting from the portion of the central passage between these plates. A tube extends through each of these plates in a manner such that the two plates and 15 the tube resemble a spool. Because of this construction, fluid can be passed into one portion of the central passage and through this tube axially of the central passage to another portion of the central passage beyond the first group of transverse bores without entering these bores. A 20 second baffle for the transverse bores at the other end of the roll is constructed in a somewhat similar manner in that two end plates which are adapted to seal off the central opening are provided and the these end plates are connected by a central pipe. However, in this baffle one 25 end of the central pipe is sealed off by the end plate, and a segment is cut from the periphery of the central pipe so that fluid may be circulated from the central passage axially through the end plate having an opening therein and thence outwardly radially of the roll to some of the 30 transverse bores. This second baffle has radial fins disposed above the central pipe which extend to the periphery of the central opening and which are adapted to divide the space between the end plates into several compartments radially outwardly of the central pipe. In this manner, fluid may be circulated axially through the open end 35 of this baffle and thence radially outwardly into one of the chambers to be transmitted to a first group of the transverse bores at this end of the mill roll. From this selected group of transverse bores, the cooling fluid is circulated 40 to only those longitudinal bores connected to these selected transverse bores and thence to the other end of the mill roll. The baffle at the first end of the mill roll has similar fins which are similarly adapted to provide a plurality of chambers between the end plates of the baffles and radially outwardly of the central pipe therein. The cooling fluid circulates from this first group of peripheral bores through the transverse passages at the latter end of the mill roll and into one of these chambers, from whence it circulates into a second group of peripheral bores to be directed back along the surface of the mill roll. After the cooling fluid has been circulated through the peripheral bores, it is discharged into one of the compartments formed by the second baffle. The second baffle has the 50 closed end plate cut out in this segment of the baffle so that the cooling fluid may be discharged again into the central passage to be conducted away from the mill roll.

In this manner, by combining baffles of the type described with a mill roll of this type in accordance with this invention, the cooling fluid can be made to circulate through the peripheral bores in the mill roll sequentially to provide greatly improved cooling of the mill roll.

For a better understanding of the nature of this invention, reference should be had to the following description when read in conjunction with the accompanying drawings, wherein:

Fig. 1 is a side elevational view of a pair of mill rolls showing one roll partially in section to illustrate the positioning of baffles therein in accordance with this invention;

Fig. 2 is a side elevational view of the baffle disposed at what may be for convenience of description termed the entrance end of the mill roll;

3

Fig. 3 is a view similar to Fig. 2 of the baffle at the discharge end of the mill roll;

Fig. 4 is a schematic view illustrating the circulation of fluid through a roll embodying this invention;

Fig. 5 is a view of the inner end plate of the entrance baffle; and

Fig. 6 is a view of the outer end plate of the discharge baffle.

Referring now to the drawings, there is shown in Fig. 1 a pair of mill rolls 10, 11 such as those commonly used in the rubber industry. These rolls are large cylindrical members each having the body portion 12 and together forming the usual nip 13 where the rubber or other material is milled. As shown, these rolls are generally provided with a cylindrical central passage 14 extending axially of the roll from one end thereof to the other. Near their periphery these rolls are provided with a multiplicity of longitudinal bores two of which are shown at 15 and 16 which extend axially of the roll from one end thereof to the other. These bores are designed to circulate a cooling or heating fluid beneath the peripheral surface of the roll to control the surface temperature thereof so that the temperature at which the material is milled may be controlled. These bores are closed at each end with plugs 17 which may be removed for cleaning of the bores.

There is provided through the body 12 of the roll a multiplicity of transverse bores 18 which communicate between the central passage 14 and the longitudinal peripheral bores. One of these transverse bores is provided at each end of the mill roll for each of the peripheral bores so that cooling fluid may be circulated from the central opening 14 to the peripheral bores. Thus referring to the structure shown in the drawings, fluid may be circulated through the transverse bore 18 at the discharge end of the mill roll 10 to the longitudinal bore 15, and thence through this bore 15 in the direction indicated by the arrow to the inlet end of the mill roll and thence through the transverse bore 19 to the central passage 14. Similarly fluid may be circulated from the central passage 14 through the transverse bore 20 to the longitudinal bore 16. The fluid is then circulated longitudinally of the roll through this bore 16 as indicated by the arrow to the transverse bore 21 through which it may be discharged into the central passage 14. Thus it will be seen that each of the longitudinal bores such as those shown at 15 and 16 has a pair of transverse bores communicating therewith and through which cooling fluid must pass to circulate through the longitudinal bores.

The heretofore described features of the mill rolls have been generally adopted in the rubber industry because of the strength requirements in these mill rolls and because of the ease with which these cooling channels may be formed. Heretofore these mill rolls have been cooled by circulating water into the central passage 14 at one end of the roll, thence through all of the transverse bores such as those shown at 19 and 21 at that end of the mill roll simultaneously to all of the longitudinal bores such as those shown at 15 and 16. The fluid is then circulated through these longitudinal bores to the other end of the mill roll from whence it circulates through the transverse bores such as those shown at 18 and 20 at that end of the mill roll to be discharged into the central passage 14 from which it is discharged from the mill roll. As pointed out above, this use of the circulating heat transfer fluid is not efficient because it is difficult to control the circulation through all of the bores simultaneously and because the circulating fluid has a relatively short pass near the periphery of the roll so that its full capacity to absorb or give up heat is not utilized. Great quantities of fluid must therefore be used, and even then the cooling cannot be controlled efficiently because flow through any one of the bores may be sluggish so that the circulating fluid has little effect upon the surface temperature of the roll at that point.

4

In accordance with this invention a pair of baffles are provided for a mill roll such as that heretofore described so that the fluid may be circulated sequentially through the longitudinal bores thereof. In the drawings, there is shown a pair of baffles a first of which 22, being here designated the entrance baffle for convenience of description, is disposed at one end of the mill roll 10. This baffle comprises an outer end plate 23 and an inner end plate 24. There is disposed between these end plates a tube 25 which extends through openings such as those shown at 26 and 27 in the end plates 23 and 24 respectively. There is thus provided a spool-like baffle having a central passage extending therethrough so that fluid may be passed from one side of the baffle to the other without entering the space between the end plates 23 and 24. As best shown in Fig. 1, the end plates 23, 24 have such a diameter that they completely close off the central passage 14 through the mill roll. In the embodiments shown in the drawings, the baffle 22 is provided with a pair of radially extending fins 28 and 29 which are fixed to the tube 25 and the end plates 23, 24. As best shown in Figs. 4 and 5, these fins 28, 29 extend to the periphery of the end plates 23, 24 so that the fins will seal off the passage 14 to form two compartments between the end plates 23 and 24, one of which would be above the fins 28, 29 and tube 25 and the other of which is beneath these members when the baffle is disposed as shown in the drawings.

A second baffle 30 which for convenience of description is termed the discharge baffle is provided for the other end of the mill roll. This baffle similarly has end plates 31, 32 and a central tube 33 extending between them. However, it will be noted that the tube 33 extends through the inner end plate 31, but is closed by the outer end plate 32 as shown in Figs. 4 and 6. Furthermore, the tube 33 is not a closed cylindrical tube but has a portion of its periphery removed. Thus in the embodiments shown in the drawings, the tube 33 has a quarter of its periphery removed as indicated at 34 in Figs. 4 and 6.

Fins are fixed to this tube 33 which extend between the end plates 31 and 32 longitudinally of the tube and which extend radially of the tube to the periphery of the plates 31, 32. These plates 31, 32 are of such a diameter that they close the central opening 14 through the mill roll 10, hence a plurality of compartments are provided by the fins on this baffle. In the embodiments shown, two fins 35, 36 are provided at the edges of the open area 34 in the tube 33. Referring next to Fig. 6, it will be noted that the outer end plate 32 has a segment cut therefrom. In the embodiments shown in the drawings, this is a quarter segment in the area 37. The baffle 30 is provided with a pair of fins 36, 38 which are disposed at the edges of this cut-out segment.

In using this invention, the baffle 22 is fixed in the central passage 14 of a mill roll so that the plates 23, 24 thereof are disposed on opposite sides of the transverse bores such as those shown at 19 and 21 at that end of the mill roll. These bores are therefore isolated from free communication with most of the length of the central passage 14. The baffle 30 is similarly disposed at the other end of the mill roll so that the plates 31, 32 are on opposite sides of the transverse bores such as those shown at 18 and 20 to close off these bores from free communication with most of the length of the central passage 14. In the embodiments shown, the baffle 22 is disposed in this central passage so that the fins 28, 29 are disposed in a horizontal position, and the baffle 30 is fixed in the central passage 14 so that the fins 35, 38 are disposed in a vertical position and the fin 36 is disposed in a horizontal position, as indicated in Fig. 4.

With the baffles thus disposed, fluid may be introduced into one end of the mill roll, such as that end having the baffle 22 therein, outwardly of the baffle. Fluid will therefore pass from the central passage 14 through the opening 26 in end plate 23, through the tube 25

and then through the opening 27 in the end plate 24 to be discharged into the central passage 14 inwardly of the baffle 22. From this central passage 14 the fluid will then pass through the opening in the end plate 31 of the baffle 30 to enter the tube 33. Since the other end of this tube is closed by the end plate 32, the fluid will escape from the tube through the opening 34 therein into the chamber formed by the walls of the central passage 14, the fins 35, 36 and the end plates 31, 32. From this chamber the fluid will circulate to selected ones of the transverse bores, such as that shown at 18' to enter selected ones of the longitudinal bores such as that shown at 15'. The fluid will circulate through these selected longitudinal bores to the other end of the roll where it will enter the corresponding transverse bores such as those shown at 19' to be discharged into a chamber formed by the walls of the central passage 14, the fins 28, 29, the tube 25 and the end plates 23, 24 of baffle 22. From this chamber the fluid will escape to selected other transverse bores such as that shown at 39 to enter further selected longitudinal bores such as that shown at 40 through which it will be recirculated to the other end of the mill roll. At this end of the mill roll, it will pass from the longitudinal bores such as that shown at 40 to further transverse bores such as that shown at 41 to enter a chamber formed by the walls of the central passage 14, the tube 33, fins 35 and 38 and the end plates 31, 42. From this chamber it will enter other of the transverse bores such as that shown at 20' to circulate through further longitudinal bores such as that shown at 16' to the other end of the mill roll. At this end of the mill roll it will enter further transverse bores such as that shown at 21' to circulate to a further chamber formed by the walls of the central opening 14, the fins 28, 29, the tube 25 and the end plates 23, 24 of the baffle 22. From this chamber, it will enter other transverse bores 42 to circulate to other longitudinal bores 43 and thence through transverse bores 44 to a chamber formed by the fins 36, 38, the tube 33 and the end plate 31 of the baffle 30. From this chamber, it will escape through the cut out portion indicated at 37 in the end plate 32 of this baffle to re-enter the central passage 14 outwardly of the baffle 30. From this central passage it may be circulated to the other mill roll 11 as indicated by the arrows in Fig. 1 to cool this mill roll in a similar manner.

From the foregoing, it will be apparent that by utilizing this invention fluid may be made to circulate through existing mill rolls so that the fluid flows through the cooling bores sequentially to cool the entire surface of the roll. It will be apparent further that this cooling fluid will be disposed adjacent the surface of the mill roll for a much longer period of time so that its full heat transfer properties may be utilized. Consequently the quantities of fluid may be reduced substantially from that heretofore used in such mill rolls. Furthermore, the cooling fluid is circulated through only a few longitudinal bores at a time, and therefore the circulation of this fluid may be controlled so that it is less likely to pass sluggishly through some of the longitudinal bores while passing rapidly through others.

Although a specific embodiment of this invention has been described, it will be apparent that the invention may be embodied in forms which differ from that described.

Having thus described my invention, what I claim and desire to protect by Letters Patent is:

1. A mill roll comprising in combination a roll having a central opening therethrough, longitudinal bores therethrough near its periphery and transverse bores at each end of said roll connecting said central opening with said longitudinal bores, baffles inserted in said central opening at each end of said central opening about the inner ends of said transverse bores, said baffles being constructed and arranged to pass fluid from said central opening through said longitudinal bores sequentially and

thereafter to pass the fluid into the discharge end of said central opening.

2. A mill roll comprising in combination a roll having a central opening therethrough, longitudinal bores therethrough near its periphery and transverse bores at each end of said roll connecting said central opening with said longitudinal bores, baffles inserted in said central opening at each end of said central opening about the inner ends of said transverse bores, the baffle at one end of said mill roll being constructed and arranged to seal off all of the transverse bores at that end of the roll from said central opening, the baffle at the other end of said central opening being constructed and arranged to seal off some of the transverse bores at that end of the roll from the inlet side of said central opening and to seal off some of the transverse bores at that end of the roll from the discharge side of said central opening, said baffles being constructed and arranged to pass fluid from said central opening through said longitudinal bores sequentially and thereafter to pass the fluid into the discharge end of said central opening.

3. A mill roll comprising in combination a mill roll having a central opening extending therethrough and a plurality of longitudinal bores adjacent the periphery thereof, said mill roll having transverse bores connecting said longitudinal bores to the central opening at each end of the mill roll, a baffle at each end of the mill roll in said central opening, each of said baffles being adapted to close off said transverse bores from said central opening, the baffle at one end of the mill roll having an opening therethrough to by-pass fluid through said central opening past said transverse bores, the baffle at the other end of said mill roll having an opening communicating with said central opening inwardly of said transverse bores for conducting fluid to some only of said individual bores, said baffles having fins adapted to pass fluid from some of said transverse bores to others of said transverse bores, whereby fluid admitted to said central opening will be circulated through said longitudinal bores sequentially.

4. Baffles for directing fluid through a mill roll having a central opening, a plurality of longitudinal bores near its periphery and transverse bores connecting said longitudinal bores to said central opening, said baffles comprising a first member for one end of the roll having ends adapted to seal off said central opening on each side of the transverse bores at that end of the roll, a tube forming a by-pass through said ends for fluid in said central opening, fins on said tube sealing off in substantially fluid tight relationship some of said transverse bores from others of said transverse bores, a second member for the other end of said roll having ends adapted to seal off said central opening on the inner side of said transverse bores at that end of the roll and to partially seal off said central opening on the outer side of said transverse bores at that end of the roll, fins between said ends sealing off in substantially fluid tight relationship some of said transverse bores from others of said transverse bores and forming chambers between said ends, said member having an opening through its inner end communicating with one of the chambers formed by said fins, said member having an opening in its outer end communicating with another of the chambers formed by said fins, said baffles being adapted to be disposed in said central opening and arranged to pass fluid through said longitudinal bores sequentially.

5. In a mill roll having a central opening therethrough, longitudinal bores about its periphery and transverse bores connecting said longitudinal bores to said central opening for circulating a fluid through said longitudinal bores, baffles for diverting fluid to circulate it through said bores sequentially, said baffles comprising a first baffle having end plates adapted to seal said central opening, each of said end plates having an opening therethrough, a tube connecting said openings for fluid move-

ment therethrough, a plurality of fins between said end plates on said tube extending to the wall of said central opening, said fins being spaced peripherally to provide chambers for intercommunication of some of said transverse bores and to seal off these bores from others of said transverse bores, a second baffle having end plates, one of said end plates being adapted to seal off said central opening at the inner end of said second baffle, fins between the end plates of said second baffle extending to the wall of said central opening, said fins being spaced peripherally to provide chambers for intercommunication of some of said transverse bores and to seal off these bores from others of said transverse bores, an end plate of said second baffle having an opening therethrough communicating with one of said chambers, the other end of said second baffle having an opening therein communicating with another of said chambers, said baffles being adapted to be disposed in said central opening to divert fluid through said longitudinal bores sequentially.

6. A mill roll comprising in combination a mill roll having a central opening extending therethrough and a plurality of longitudinal bores adjacent the periphery thereof, said mill roll having transverse bores connecting said longitudinal bores to the central opening at each end of the mill roll, a first baffle having end plates sealing off said central opening on each side of said transverse bores at one end of the roll, each of said end plates having an opening therethrough, a tube connecting said openings in the end plates for fluid movement therethrough, a plurality of fins between said end plates on said tube extending to the wall of said central opening, said fins being spaced peripherally of the baffle to provide cham-

bers for intercommunication of some of said transverse bores and to seal off these bores from others of said transverse bores, a second baffle having end plates, a first of said end plates being adapted to seal off said central opening from said transverse bores at the other end of the roll inwardly of said transverse bores and a second of said end plates being adapted to partially seal off said central opening from said transverse bores outwardly of said transverse bores, fins between the end plates of said second baffle extending to the wall of said central opening, said fins being spaced peripherally of the baffle to provide chambers for intercommunication of some of said transverse bores and to seal off these bores from others of said transverse bores, the inner end plate of said second baffle having an opening therein communicating with one of said chambers, the outer end plate of said second baffle having an opening therein communicating with another of said chambers, whereby fluid admitted to the first end of said mill roll will pass through said tube in said first baffle into a chamber of said second baffle and thence through the longitudinal bores sequentially and then be discharged into the central opening at the other end of the mill roll.
